(57) **CLAIM**

The ornamental design for a double-sided LED makeup mirror as shown and described.

DESCRIPTION

FIG. 1 is a front, right perspective view of a double-sided LED makeup mirror showing my new design;

FIG. 2 is another rear, left perspective view thereof;

FIG. 3 is another rear, right perspective view thereof;

FIG. 4 is a front view of FIG. 1;

FIG. 5 is a rear view thereof;

FIG. 6 is a right view thereof;

FIG. 7 is a left view thereof;

FIG. 8 is a bottom view thereof; and,

FIG. 9 is a bottom view thereof.

The broken lines shown on the drawings depict portions of the double-sided LED makeup mirror that form no part of the claimed design.
